UNITED STATES PATENT OFFICE.

BENJAMIN E. D. STAFFORD, OF PITTSBURGH, PENNSYLVANIA, ASSIGNOR TO FLANNERY BOLT COMPANY, OF PITTSBURGH, PENNSYLVANIA.

STAY-BOLT FOR BOILERS.

1,236,224.

Specification of Letters Patent.

Patented Aug. 7, 1917.

Application filed November 30, 1914. Serial No. 874,828.

To all whom it may concern:

Be it known that I, BENJAMIN E. D. STAFFORD, a citizen of the United States, and a resident of Pittsburgh, in the county 5 of Allegheny and State of Pennsylvania, have invented certain new and useful Improvements in Stay-Bolts for Boilers; and I do hereby declare the following to be a full, clear, and exact description of the invention, such as will enable others skilled 10 in the art to which it appertains to make and use the same.

My invention relates to an improvement in flexible stay bolts for boilers, the object 15 being to provide a composite bolt that will be as rigid longitudinally as the ordinary bolt, but flexible laterally so as to permit the bolt to yield or give to accommodate itself to the unequal lateral movements of 20 the inner sheets, thereby preventing buckling or undue straining of either sheet.

With this object in view my invention consists in the parts and combinations of parts 25 and in the details of construction as will be more fully explained and pointed out in the claims.

In the accompanying drawings, Figure 1 is a view in section of one embodiment of 30 my invention, and Figs. 2, 3 and 4 are views of modifications.

1 represents a tubular bolt the outer end 2 of which is enlarged and threaded externally, for its attachment to the outer sheet of the boiler, and the inner or smaller 35 end also threaded externally for its attachment to the inner sheet of the boiler. This tube 1 is preferably made of stay bolt metal, or a mild grade of open hearth steel, and is corrugated as shown, the corrugations being either circumferential or spiral.

The head 2 is also threaded internally for the engagement therewith of the externally threaded head of the inner bolt 3, which is preferably solid but much smaller in cross 45 section than the ordinary solid stay bolt. This inner bolt 3 passes longitudinally through the outer hollow bolt and is preferably welded to the inner end of the latter, and projects beyond said inner end so that 50 it may be upset as at 4, against the outer face of the inner sheet of the fire box or boiler.

With this construction the connections between the two bolt members 1 and 3, are at 55 the ends of the outer members and in the

planes of the inner and outer sheets of the boiler, consequently there can be no give longitudinally except such as may result from the stretching of the inner member. The two members are disconnected from each other intermediate their ends, and it is intended that the metal in the combined cross sectional area of the two members shall about equal that of the metal in the single rigid bolt now in common use, but by making it of two parts instead of one, it will be flexible laterally and free to give or yield under the movements of the two sheets, without unduly straining either and without injury to the bolt.

In the construction shown in Fig. 2 the inner end of the tubular member 1^a of the bolt is threaded internally, and the inner solid member 3^a is provided with a rounded head 3^b which rests against the curved seat 1^b formed within the head 2 of the outer member 1^a of the bolt, and with an externally threaded inner end which engages the threaded end of the outer member of the bolt, for securing the two parts of the bolt against separation or independent longitudinal movement. The inner threaded end of the inner member 3^a of the bolt, passes through the inner end of the outer member 1^a, and is screwed into the inner sheet, the head 2 of the outer member, being screwed into the outer sheet as in the previous construction. With this construction, the threaded connection between the inner and outer section of the bolt, and the contact between head 3^b and seat 1^b prevent the escape of any steam through the outer member of the bolt.

In Fig. 3, the inner member is provided with spherical heads, one of which 6 is mounted in the outer section 1^c near the inner end of the latter, while the other 3^c rests against a curved seat in the head 2 as in the previous construction.

In assembling this latter bolt, the inner bolt is inserted through the head 2, and the outer member is then shaped by suitable tools to lock the head 6 within its seat in said outer member. The extreme inner end of the outer section 1^c, is reduced and threaded to engage the inner sheet of the boiler.

In the construction shown in Fig. 4, the head 2^a of the inner member 3^a of the bolt, is enlarged and threaded externally to engage the outer sheet. The shank of the bolt

is also provided adjacent the head 2 with a threaded section 3^a to which the outer member 1^a of the bolt is screwed, the inner end of said outer member being secured to the inner threaded end 3^c of the bolt, the said threaded sections 3^a and 3^c being of greater diameter than the shank. The outer member of the bolt, is in this instance merely a sleeve secured to the bolt proper and reinforcing the latter between its ends.

In all of these constructions the shank of the bolt is in two parts, one within the other, the outer part being constructed to bend freely and the inner part sustaining it longitudinally.

If desired the inner member may be provided with longitudinal slits 8 as shown in Fig. 4 which add to the flexibility of the same without impairing its capacity to resist longitudinal strains.

It is evident that many slight changes might be resorted to in the relative arrangement of parts shown and described without departing from the spirit and scope of my invention. Hence I would have it understood that I do not wish to confine myself to the exact construction and arrangement of parts shown and described except as set forth in the claims annexed.

Having fully described my invention what I claim as new and desire to secure by Letters-Patent, is:—

1. As a new article of manufacture, a flexi-

ble stay bolt composed of an outer corrugated tube, and a bolt within the tube, the tube and bolt being connected adjacent their ends, and disconnected at intermediate points so as to permit the bolt as whole to give or yield laterally.

2. As a new article of manufacture, a flexible stay bolt composed of an outer corrugated tube having an enlarged externally threaded hollow head and a bolt member within said tube and having a head within the head of the tube, the opposite ends of said tube and bolt member being connected, the said tube and bolt member being disconnected at points intermediate their ends so as to permit the bolt as a whole to flex laterally.

3. In a flexible stay bolt, the combination of an outer corrugated tube having an enlarged head threaded externally and internally, and a bolt member within said tube and having an externally threaded head to engage the internal thread in the head of the tube, the other end of the bolt member being welded to the smaller end of the tube.

In testimony whereof, I have signed this specification in the presence of two subscribing witnesses.

BENJAMIN E. D. STAFFORD.
